EDWARD T. SMITH AND JOSEPH S. WINSTON, OF NEW YORK, N. Y.

Design No. 4,387, dated October 4, 1870.

DESIGN FOR A COFFIN.

The Schedule referred to in these Letters Patent and making part of the same.

To all whom it may concern:

Be it known that we, EDWARD T. SMITH and JOSEPH S. WINSTON, of New York city, in the State of New York, have invented and produced a new and original Design for a Coffin End, of which the following is a specification.

It is rounded slightly at the center of the head, rounded quickly at the parts corresponding to the corners, and flared.

The accompanying drawing forms a part of this specification.

Figure 1 is a plan view, and
Figure 2 is an elevation.

The nature of our design is fully represented in these figures.

We claim—

The design for a coffin end, as shown.

E. T. SMITH.
J. S. WINSTON.
